UNITED STATES PATENT OFFICE

JOHN TOMEK, OF TRENTON, NEW JERSEY, ASSIGNOR TO W. & J. SLOANE MANUFACTURING COMPANY, A CORPORATION OF NEW JERSEY

ORNAMENTAL SURFACE COVERING

Application filed June 1, 1926. Serial No. 112,823.

This invention relates to improvements in ornamental surface coverings, and while the invention is capable of use in connection with ornamental surface coverings generically, it is particularly adapted to the manufacture of floor covering such, for example, as linoleums and the like.

The principal objects of the invention are to improve the construction of linoleum and similar surface coverings and processes of making the same and to provide a floor covering which, when completed, will in every respect resemble the floor known as "Dutch" tiling.

15 "Dutch" tiling floors are formed by laying tiles of different colors in spaced relation to one another, the space between the tiles being partially filled with the mortar in which the tiles are laid. In this particular type of floor, 20 however, the exposed surface of the mortar does not extend to a point where it is flush with the exposed surface of the tiles and thus the exposed surface of the entire floor is in intaglio and relief, the mortar being in 25 intaglio, and the tiles in relief.

While the invention is particularly designed to be applied to the manufacture of linoleum in imitation of Dutch tiling, certain features thereof may be applied to the 30 manufacture of surface coverings other than linoleum and certain features also may be applied to the manufacture of linoleum and similar surface coverings having designs certain portions of which are in relief but not 35 made to resemble particularly Dutch tiling or any other kind of tiling.

The invention will be clearly understood from the accompanying drawings which illustrate it in its preferred forms and the following detailed description of the construction 40 therein shown.

In the drawings,

Figure 1 is a plan view of a section of ornamental surface covering constructed in 45 accordance with one form of the present invention;

Figure 2 is a detail sectional view illustrating one step in the method of forming an ornamental surface covering in accordance 50 with one form of the present invention;

Figure 3 is a detail sectional view on an enlarged scale of the finished ornamental surface covering constructed in accordance with that form of the invention disclosed in Figures 1 and 2;

Figure 4 is a detail sectional view illustrating one step in a slightly modified method of forming an ornamental surface covering; and

Figure 5 is a detail sectional view on an enlarged scale, of the finished ornamental surface covering constructed in accordance with the modified method hereinbefore referred to.

In carrying out the present invention a suitable backing, such as designated by the numeral 10, is employed. This backing 10 is more or less common in the manufacture of linoleums and the like, and may consist of any material suited for the purpose, of which burlap is one example.

In making inlaid linoleum for example, there are two distinct processes well known in the art for many years, the "moulded" and the "straight line." In the moulded process, the linoleum material in granular form is applied in the desired pattern and colors to a backing and then compressed. The edges of the colors interlace and give to the inlays a ragged-edge outline characteristic of the moulded product and which is objectionable to the public because it looks like poor workmanship. The so-called "straight-line" inlaid product is preferred because of the clearly defined outlines of the tesserae, whether they are actually straight or not. The so-called "straight-line" inlaid is made by cutting out from previously-formed sheets of compacted linoleum tesserae of the desired shapes and assembling them together in the same manner as sliced animals or sliced maps are assembled, with the vertical edges of the various parts closely abutted. The sheet is then consolidated in a flat-faced heated press.

If an imitation of tiling for example, is made by either of the above processes and it is desired that the tiling or tesserae stand in relief with respect to the intervening mortar-representing joints for example, the grooves have been formed by suitably shaped

ribs on the face of the press. But this is objectionable for several reasons. It has been found that such ribs, due to their somewhat shearing effect, tend to open or weaken the joints between tesserae made by the "straight-line" method. Further, it is extremely difficult to accurately match the ribs with the mortar-representing joints whether the sheet is made by the moulded or "straight-line" method. Readjustment of the sheet with reference to the press is necessary at each press operation. Even when this is done the ribs do not always match properly due to slight movement of the tesserae, or stretch of the burlap backing in the preliminary consolidating press. Consequently a large proportion of the product is "off" somewhat in the indentation and has to be discarded or sold as a "second." Furthermore the ribs accurately reproduce the indentations at each "repeat" of the press. In successive repeat areas these joints reproduce themselves with absolute accuracy. In every repeat the groove width and shape are exactly the same as in every adjacent repeat therein. The product is hard and mechanical looking and undesirable for this reason.

In ordinary hand-laid ceramic tiling there are obvious irregularities due to inaccuracy of tile-positioning, tile-outhing and joint-construction which result in inaccuracies of joint width, groove shape, etc.,—so that even if the pattern is reproduced in the repeats (as it usually is) the inaccuracies which occur in one repeat are not necessarily reproduced in the successive repeats. These inaccuracies are present in all hand-laid work. It has been the desire of the trade to reproduce in a linoleum floor covering for example, such "irregular irregularities" in order more nearly to simulate hand-laid work. I have accomplished this by my process.

In carrying out my invention as illustrated in the drawings, and assuming that a tile-representing linoleum product is to be produced, I assemble on a backing 10 tesserae of the desired shapes and colors and separated from each other by narrow spaces, together with lower-lying joint-representing material. In Fig. 2 I have shown the tesserae 14 separated by strips of joint-representing material indicated at 12. In Fig. 4 the tesserae are represented by 24 and the lower-lying strips as 20. The tesserae and strips are formed from already-compacted but still somewhat soft linoleum material. They are preferably formed as in the ordinary "straight-line" method, i.e., by cutting them out of sheets of uncured linoleum of the desired colors. They are then still somewhat malleable, i.e., deformable. When the mortar-representing material is in the form of strips and it is desired that the joints should be represented by sunken areas between the tesserae, I may arrange the elements by mak-

ing the tesserae 14 (or 24) thicker than the intervening joint-representing strips 12 (or 20). In Fig. 2 the strips and tesserae have abutting vertical faces, while in Fig. 4 the tesserae somewhat overlie inclined faces 25 of the strips. This latter is of advantage in some cases, for when the material which is to represent the mortar joint (for example) extends under the adjacent tesserae the tesserae need not be so accurately positioned, for slight inaccuracies of location (such as when a tessera is slightly askew) are immaterial.

The assembled sheet is then subjected to compression in a flat-faced press such as is ordinarily employed in consolidating "straight-line" inlays. Such presses are usually heated at least on the face which contacts with the upper face of the sheet. This compaction and consolidation by heat and pressure is often termed "vulcanization" in the linoleum industry for it is similar in some respects to the pressure vulcanization in the rubber industry. As the already-compacted tesserae are still somewhat soft and malleable, the pressure causes them to be expanded laterally somewhat and they will flow slightly over the intervening joint-representing strips, as indicated rather diagrammatically in Figs. 3 and 5. This lateral flowing of the edges of the tesserae results in a more or less downwardly inclined margin, as indicated at 16 in Fig. 3. The amount of downward curvature of course will depend upon the consistency of the tesserae material and the amount of pressure applied. The pressure should however be relieved before the lateral flow has entirely closed up the spaces between the tesserae. The intervening joint-representing material will therefore be exposed to view. Fig. 1 represents rather diagrammatically the resultant product.

The pressure of course causes the adjacent faces of the tesserae and the intervening strips to be welded together as it were, into a substantially homogeneous sheet. The sheet is of course subjected to the ordinary curing and drying operation usual in the linoleum industry. The final sheet therefore comprises tesserae in relief with respect to the narrow mortar-representing strip portions.

I have found that in carrying out the above process, several advantageous results are obtained. As above pointed out, the trade prefers a "straight-line" product as distinguished from the ragged-edge product unavoidable in the moulded process. My final product has edges which are typical of the "straight-line" inlay because although the edges are expanded or caused to flow laterally somewhat, they still retain the clearly defined outline which differentiates the ordinary "straight-line" inlay from the moulded. The grooves also register accurately in every

case with the outlines of the tesserae. This is impossible in a product which is first made flat-faced and then indented by ribs. In other words the sunken areas in my product occur exactly where they should occur and never can be "off" in any such respect.

Furthermore slight irregularities of joint width and tile outline occur. Such an inaccuracy may occur at one edge of one tile and never reoccur again throughout the length of the goods no matter how many repeats of the pattern there are. For example, supposing there are three different colors of tesserae, one blue, one green and one red. These are cut out of separate sheets of colored material. In producing such sheets, the material is supposed to be homogeneous as far as possible and one sheet as much alike in consistency as the other. Absolute correspondence cannot be obtained. If one sheet were produced yesterday and another sheet produced today, or if one is a little different in ingredients from the other, as must occur often, the different tesserae under pressure will flow somewhat differently from others of the tesserae. The result is that while the outlines are clearly defined, the joint width or groove shape will not be exactly the same throughout the piece. Also if some of the tesserae are placed slightly askew, whether intentionally or not, as they may be especially when the joint-representing material underlies the tesserae, the appearance of the joint or the groove width will again vary somewhat. Such unavoidable inaccuracies result in what might be termed irregular irregularities. In every repeat area irregularities will be found which may not reoccur in any successive repeat area.

The practical result is that by my process there is produced a product which has the tesserae in relief with clearly defined edges, with exactly-located joint-representing sunken areas and with slight inaccuracies which closely simulate the unavoidable inaccuracies of hand-laid ceramic tiling.

It is to be understood that the invention is not limited to the particular construction and mode of operation of the illustrated embodiment of the invention but that the invention may be embodied in other forms within the scope of the claims.

What is claimed as new is:

1. The method of forming ornamental surface coverings in intaglio and relief, which consists of applying to a suitable backing material, ornamentation sections of different thicknesses and subsequently causing the ornamentation sections of greater thickness to overlie and become an integral portion of those sections of less thickness.

2. The method of forming ornamental surface coverings which consists in forming sections of ornamental material in predetermined shapes and of different thicknesses, applying these sections to a suitable back-

ing material and subsequently subjecting the whole to pressure to cause those sections of greater thickness to partially overlie those sections of less thickness and to stand out in relief with respect thereto in the finished product.

3. The method of forming ornamental surface coverings which consists in applying to a suitable backing material a plurality of relatively long narrow sections or strips of moldable material in such manner as to divide the entire area into spaces of predetermined size and shape, subjecting said strips to pressure to increase their lateral dimensions at one point in their thickness, filling the spaces between the strips with a moldable material to a greater thickness than that of the strips, and subsequently compressing the whole into a substantially integral mass.

4. The method of forming an ornamental surface covering which comprises applying to a suitable backing shaped portions of moldable stock and adjacent lower-lying portions, and applying sufficient pressure to the exposed faces of the former to compact the same but leave them in relief and cause their margins to spread sidewise.

5. The process of producing a linoleum sheet, which consists in taking tesserae which have been cut of uncured linoleum sheets and arranging them in spaced relation with intermediate lower-lying and already-compacted linoleum material, and applying pressure to the exposed faces of said tesserae in such manner as to consolidate the parts of the pattern and cause the tesserae to spread sidewise, and then relieving the pressure at such time as to leave between the tesserae sunken areas in which the lower-lying material is exposed to view.

6. The method of forming a linoleum sheet which consists in applying on a suitable backing and in a desired pattern sections of already-compacted but still mouldable linoleum stock, some of which are in relief, and applying sufficient pressure to the exposed faces of those which are in relief to cause their margins to spread sidewise sufficiently to overlap and adhere to the exposed faces of the adjacent lower-lying sections, and relieving the pressure before the intermediate portions are covered.

7. A linoleum sheet comprising a pattern of compacted linoleum tesserae, some of which are in relief, the margins of the latter overlying and adhering to the outer faces of the adjacent lower-lying sections, with portions of the latter exposed to view in the sunken areas.

8. A linoleum sheet comprising spaced tesserae of compacted linoleum having downwardly-inclined margins with substantially straight-line edges separated by and overlying the upper faces of intervening exposed lower-lying compacted linoleum, the ele-

ments of the sheet being formed into a substantially integral mass.

9. The method of forming a linoleum sheet which consists in assembling into a desired design spaced tesserae of already compacted while still somewhat malleable linoleum and interposed strips of compacted linoleum whose faces lie below those of the tesserae, exerting pressure on the exposed faces of said tesserae sufficient to cause the tesserae and strips to be welded together, and relieving the pressure before the tesserae faces are depressed to the level of the faces of the strips, whereby a sheet with tesserae in relief is produced.

10. The method of forming a linoleum sheet which consists in cutting out of differently colored sheets of compacted and somewhat malleable linoleum tesserae of the desired shape, assembling into a desired design such tesserae in spaced relation together with interposed strips of compacted linoleum whose faces lie below those of the tesserae, exerting pressure on the exposed faces of said tesserae sufficient to cause the tesserae and strips to be welded together, and relieving the pressure before the tesserae faces are depressed to the level of the faces of the strips, whereby a sheet with tesserae in relief is produced.

11. A linoleum sheet comprising a suitable backing, a design made up of separated compacted linoleum tesserae in relief with respect to strips of compacted linoleum interposed and exposed between said tesserae, the edges of said tesserae overlapping and being surface-welded to the upper surfaces of adjacent strips, both said tesserae and strips being in contact with and adhering to said backing.

12. The process of producing an inlaid sheet with tesserae in relief, which consists in arranging into the desired pattern previously-consolidated and shaped tesserae of relatively soft material somewhat spaced from each other, together with lower-lying portions of similar material exposed between the tesserae, and exerting downward pressure upon the exposed faces of the tesserae sufficient to cause them to spread sidewise, and relieving the pressure before the spaces between the tesserae are closed up, whereby intervening grooves are produced and irregularities of joint width and groove shape occur which do not necessarily reoccur in successive repeat areas.

13. The process of producing a patterned linoleum sheet which comprises arranging in a suitable pattern and in spaced relation previously-compacted and shaped but still malleable tesserae in relief with respect to other linoleum material exposed to view between and also extending under the adjacent tesserae, and applying pressure to the exposed faces of the tesserae in such manner as to weld together the parts of the sheet and cause

the tesserae to spread somewhat sidewise but not enough to cover the intervening areas, thereby producing sunken areas between the tesserae in which the intervening material is visible, the margins of the tesserae being clearly defined—as compared with those of moulded inlaid linoleum—and having visible irregularities which do not reoccur in successive pattern-repeat areas.

14. A linoleum sheet comprising a pattern of compacted linoleum tesserae whose edges are clearly defined—as compared with those of moulded inlaid linoleum—and which tesserae are in relief with respect to and are welded to intervening exposed compacted linoleum which extends under the adjacent tesserae, the margins of the tesserae forming in the sunken areas visible irregularities which do not reoccur in successive pattern-repeat areas.

Signed at New York city this 25th day of May, 1926.
